3 Claims. (Cl. 252—49.7)

This invention relates to improved liquid hydrocarbon compositions and more particularly to such compositions containing an organometallic additive.

This application is a continuation-in-part of application Serial No. 735,710, filed May 16, 1958. It is an object of this invention to provide improved liquid hydrocarbon compositions. Another object is to provide an improved fuel containing a particular class of organometallic compounds as additives. A further object is to provide fluids for addition to fuels to improve the combustion characteristics thereof. Another object is to provide improved lubricating oil compositions. Still other objects will be clear from the following description of the invention.

The present invention is directed to the use of cycloheptatriene transition metal coordination compounds of the Group VIB metals, as additives for liquid hydrocarbon compositions.

The coordination compounds employed as additives in the instant invention constitute coordination compounds having a cycloheptatriene compound coordinated with a transition metal of Group VIB of the Periodic Table. Further stabilization of the aforementioned transition metal containing compounds can be effected through additional coordination with other electron donating groups or another cycloheptatriene molecule. The sum of all electrons donated to the transition metal and the atomic number of said metal in the additive compounds is equal to the atomic number of the next higher rare gas with respect to said metal. Most preferred compounds may be represented by the formula:

where A is a cycloheptatriene compound coordinated to the group VIB metal atom M. Examples of these compounds are the cycloheptatriene chromium tricarbonyls, cycloheptatriene molybdenum tricarbonyls and the cycloheptatriene tungsten tricarbonyls and the like.

Before illustrating the use of the cycloheptatriene coordination compounds as additives according to this invention, it is convenient to further define the scope of the coordination compounds. The term coordination as employed in this invention means the electron donating mechanism by which an inert gas structure in the outer electron shell of the metal atom is achieved. Thus, the term coordinated can be defined as non-ionic bonding including both covalent and coordinate covalent bonding. By covalent bonding is meant a bond formed by the sharing of two electrons between bonded atoms, each atom contributing one electron. By coordinate covalent bonding is meant a bond in which two or more electrons are shared by the bonded entities but one entity supplies all bonding electrons.

The compounds employed in the compositions encompassed by this invention can consist of two or three primary constituents. The most preferred compounds have three primary constituents a cycloheptatriene molecule, the Group VIB metal atom and three carbonyl groups. Other preferred compounds may possess electron donor groups other than the carbonyl group, e.g. compounds such as cycloheptatriene chromium benzene and cycloheptatriene molybdenum toluene are applicable.

Another type of compound suitable for use according to the invention are the bis(cycloheptatriene) Group VIB metal compounds. A suitable combination of donors, producing the maximum possible covalency on the metal atom will produce the desired type of coordination compounds of this invention. In the compounds the sum of all coordinated electrons of each transition metal plus the atomic number of said metal is equal to the atomic number of the next higher rare gas with respect to the metal. It is to be noted that the cycloheptatriene compound, the other electron donors and the metal electron acceptor are the sole substituents of the compounds.

The coordination compounds employed as additives in this invention are metallic coordination compounds in which the metal is a transition metal selected from Group VIB of the Periodic Chart of the Elements as shown in the "Handbook of Chemistry and Physics," 38th edition, The Chemical Rubber Publishing Co., Cleveland, Ohio, 1956. These metals are chromium, molybdenum and tungsten.

Another primary constituent of the additive compounds of the present invention is a cycloheptatriene compound. Cycloheptatriene is a conjugated cyclic hydrocarbon having 3 carbon-to-carbon double bonds in a 7 carbon atom ring. The compound has the formula C_7H_8 . It can be represented by the following formula:

The cycloheptatriene compound which is a constituent of the compounds used in this invention can be selected from a wide range of cycloheptatriene organic compounds. The applicable compounds include, for example, cycloheptatriene, 1 - cycloheptatrienyl cycloheptatriene, 1 - methylcycloheptatriene, 2 - isopropylcycloheptatriene, 1,4 - di-ethylcycloheptatriene, 4 - phenylcycloheptatriene, 3-decylcycloheptatriene, 1-tert-butylcycloheptatriene, 1,3-diisopropylcycloheptatriene, 1 - hydroxycycloheptatriene, 1-cycloheptatrienyl carboxylic acid propylester, 3-cycloheptatrienyl butylether, 2-N-ethylcycloheptatrienyl amine, 1-methylaminocycloheptatriene, 1-chlorocycloheptatriene, 3,5-di-methoxycycloheptatriene, 1-di-methoxymethylcycloheptatriene, 3 - isopropyl - 1 - phenylcycloheptatriene, 1-methyl-4-phenylcycloheptatriene, 3 - hydroxymethylcycloheptatriene, 1-cycloheptatriene carboxylic acid, 1-cycloheptatriene and the like. Those compounds having up to about 14 carbon atoms are preferred since they lead to more easily recoverable products and constitute the most readily available cycloheptatriene compounds.

The third primary constituent of the new compositions of matter of the present invention is designated as an electron donating group capable of coordinating with the metal atom in the novel compounds of this invention and donating thereto 1 through 6 electrons each. This is to say, that these groups are capable of sharing electrons with the metal atom so that the metal achieves a more stable structure by virtue of the coordination.

The electron donating groups applicable to the compounds of this invention may either be organic or inorganic entities which are capable of existing as ions, such as hydrogen, the cyanide groups, isocyanide group, alkyl, and the like. For the sake of clarity, the electron donating group can best be described by combining these groups according to the number of electrons they are capable of donating. The electron donors are discussed below.

The Group VIB metal atoms in the additive compounds have the electronic configuration of the next higher inert gas. Preferably the metal atoms also have a co-

ordination number of six, or in other words six pairs of coordinated electrons are donated to the central metal atom. These preferred compounds are in general, more readily prepared and of higher stability.

One type of preferred compounds contains two rings, which each donate three pairs of electrons. Non-limiting examples of this type of compounds are cycloheptatriene molybdenum benzene and decycloheptatriene chromium.

Another type of preferred compounds are those that contain a cycloheptatriene ring (which donates three electron pairs) and three moles of a two-electron donor. Of the two-electron donors described below, carbon monoxide is preferred. Thus the more preferred compounds are the cycloheptatriene chromium tricarbonyls the cycloheptatriene molybdenum tricarbonyls and the cycloheptatriene tungsten tricarbonyls. The metal atoms in these compounds have the preferred coordination number, six, since the cycloheptatriene donates three pairs of electrons and the 3 carbonyl groups each donate one pair.

The cycloheptatriene Group VIB metal tricarbonyls are more preferred than the two ring compounds described above since they are more readily prepared.

Other cycloheptatriene Group VIB metal compounds that contain electron donors of the type described below which do not have a coordination number of six are suitable but not preferred.

Donors capable of sharing a single electron with a metal atom include monovalent organic radicals such as the hydrogen atoms, the halogens (fluorine, chlorine, bromine, iodine) and the cyanide group CN. These groups function as electron donors by combining an electron with an electron of the metal atom to form a single covalent bond. It is to be noted that when the electron donor group bonded to the metal atom in a compound of this invention is or contains a monovalent organic radical this organic radical can contain up to about 20 carbon atoms. In most instances, such monovalent organic groups are hydrocarbon or substituted hydrocarbon groups containing between 1 and 16 carbon atoms. These preferred organic radicals include alkyl, aryl, alkaryl, 35 aralkyl radicals and the like. Furthermore, acyclic unsaturated derivatives can be employed such as alkynyl and alkynyl derivatives. Such substituents as nitro, amino, amido, thio, sulfate, carboxy, carbamide, oxy, hydroxy, alkoxy, aryloxy, and their corresponding thio derivatives may be present on the hydrocarbon radical. In general, 45 however, those substituents preferred are those containing chalkogen, that is, oxygen or sulfur, and nitrogen atoms, such as the foregoing nitro, nitroso, amino, oxy, hydroxy, thio groups. Specific examples of those hydrocarbon groups preferred as monovalent organic substituents in the 50 compositions of the instant invention are methyl, ethyl, propyl, octyl, 4-phenyl octyl, 2-phenyl heptyl, eicosyl, 1-nitropropyl, 3-amino-n-octyl, and the like. Illustrative of compounds containing donors capable of sharing a single electron with a transition metal atom are cycloheptatriene (cyclopentadienyl) chromium methyl, cycloheptatriene molybdenum (diethyl) dicarbonyl and the like.

Groups capable of sharing two electrons with a metal atom include carbon monoxide, ammonia, primary-, secondary-, and tertiary-amines, cyclic nitrogen compounds wherein the nitrogen is in the trivalent state, organo phosphine compounds, phosphines, halides, arsines, stibines, bismuthines; mixed hydroorganic phosphines, stibines, arsin, and bismuthines; isonitriles, and the like. Examples of the metal coordination compounds of this invention which contain such donating groups include cycloheptatriene molybdenum tricarbonyl dimer, cycloheptatriene chromium tris(triphenylphosphine) cycloheptatriene chromium bis(methyl isonitrile), carbonyl and the like.

The nitrosyl group, NO, is an example of an entity capable of donating three electrons to a metal atom. Examples of compounds containing groups of this nature include cycloheptatriene tungsten dinitrosyl, cycloheptatriene chromium dinitrosyl, and the like.

In the coordination compounds employed in this invention certain groups are capable of coordinating four electrons with the metal atom. These four electron donor groups include organic diamines, diphosphines, diarsines, distibines, aliphatic diolefins, and alkyne molecules. Typical examples of the compounds of the instant invention containing such donor groups are cycloheptatriene chromium bis(methylene diamine) carbonyl, cycloheptatriene tungsten(butadiene) carbonyl and the like.

The cyclopentadienyl radical is capable of contributing 5 electrons to the coordination compounds utilized in this invention. The cyclopentadienyl radical found in the compounds contains from 5 to about 13 carbon atoms and thus includes substituted cyclopentadienyl hydrocarbon radicals having up to 8 carbon atoms in one or more side chain substituents which may be bonded to more than one ring carbon atom. Examples of such radicals include the octylcyclopentadienyl radical, the methylcyclopentadienyl radical, the indenylcyclopentadienyl radical and the like. Examples of the compounds employed in this invention which contain a cyclopentadienyl radical include cycloheptatriene cyclopentadienyl chloromolybdenum, cycloheptatriene ethylcyclopentadienyl ethyltungsten and the like.

Aromatic compounds, that is, compounds containing a benzene nucleus, are capable of coordinating with a metal atom. These aromatic compounds act as 6 electron donors when coordinately bonded to the metal atom. Aryl and alkyl substituted aromatic compounds are applicable to the present compounds, as are fused ring compounds having a benzene nucleus. Aromatic compounds having from 6 to 18 carbon atoms are generally preferred in the present compounds. Examples of these are benzene itself, mesitylene, toluene, biphenyl tetraline and m-hexylbiphenyl. Examples of the present compounds containing an aromatic coordinating group include 1-ethylcycloheptatriene (toluene) molybdenum 1-phenylcycloheptatriene (mesitylene) tungsten, cycloheptatriene (ethylbenzene) chromium, and the like.

The new compositions of matter of the instant invention comprise a liquid hydrocarbon containing from about 0.015 to about 10 grams per gallon of a transition metal of Group VIB. The metal is employed as a cycloheptatriene coordination compound as defined above. It is found that when such compositions are employed in the operation of an ignition internal combustion engine, advantages are achieved which are unrealized in compositions which do not contain the compounds. Additionally, they are useful in other hydrocarbon stocks such as jet fuel, diesel fuel and heating fuels and lubricants.

A preferred composition of the present invention comprises a composition containing from about 0.03 to about 6 grams of a Group VIB metal per gallon of fuel as a cycloheptatriene coordination compound. This range of metal concentration is preferred as it is found that superior results stem from its use.

A particular advantage of the additives of the present invention is the fact that by proper selection of the co-ordinating groups, that is, the cycloheptatriene and other different electron donors, compounds having tailor-made characteristics can be obtained. Thus, by the proper selection of the coordinating group it is possible to prepare compounds possessing different degrees of stability, volatility, and solubility. Likewise, the selection of these constituents also enable the preparation of compounds of applicability in diverse liquid hydrocarbons.

The compounds employed in this invention can be used in fuels and lubricating oils by themselves or together with other additive components such as, in the case of gasoline, scavengers, deposit modifying agents containing phosphorus and/or boron, and also other antiknock agents, such as organolead compounds. For example, fuels containing organolead antiknock agents can contain from about 0.01 to about 8 or more grams of lead per gallon.

The compounds can be added directly to the hydrocarbon fuels or lubricating oils and the mixture subjected

to stirring, mixing, or other means of agitation until a homogeneous fluid results. Alternatively, the cycloheptatriene metal compound may be first made up into concentrated fluids containing solvents such as kerosene, toluene, hexane, and the like, as well as other additives such as scavengers, antioxidants and other antiknock agents, for example, tetraethyllead. The concentrated fluids can then be added to the fuels. In such manner new compositions of matter comprising fluids particularly adapted for addition to hydrocarbon fuels can be produced. Such fluids consist essentially of an organolead antiknock agent, halohydrocarbon scavengers therefor, and a cycloheptatriene metal coordination compound of a transition metal of Group VIB. When employed in these fluids the cycloheptatriene metal coordination compound is present in amounts so that for each gram of lead present there is from about 0.01 to about 10 grams of a transition metal of Group VIB. A preferred range comprises those compositions wherein the relative concentrations of transition metal are adjusted so that from about 0.1 to about 6 grams of Group VIB transition metal is present for each gram of lead as an organolead compound.

As the organolead antiknock agent which is one of the ingredients of certain of the compositions of this invention, organolead compounds in general may be used. Preferably, however, hydrocarbon lead compounds such as tetraphenyllead, tetratolyllead, and particularly tetraalkyllead compounds wherein the alkyl radical contains between 1 to 4 carbon atoms, such as tetramethyllead, tetrapropyllead, and the like are employed.

When halohydrocarbon compounds are employed as scavenging agents, the amounts of halogen used are given in terms of theories of halogen. A theory of halogen is defined as the amount of halogen which is necessary to react completely with the metal present in the antiknock mixture to convert it to the metal dihalide. In other words, a theory of halogen represents two atoms of halogen for every atom of lead present. In like manner, a theory of phosphorus is the amount of phosphorus required to convert the lead present to lead orthophosphate, $Pb_3(PO_4)_2$, that is, a theory of phosphorus based on lead represents an atom ratio of two atoms of phosphorus to three atoms of lead. When based on chromium, a theory of phosphorus is equivalent to one atom of phosphorus for every one atom of chromium, that is, sufficient phosphorus to convert chromium to chromium orthophosphate, $CrPO_4$. Similar considerations apply to the other metals.

In employing the compounds of this invention together with scavengers, an antiknock fluid for addition to hydrocarbon fuels is prepared comprising a metal coordination compound together with various scavengers such as halogen-containing organic compounds having from 2 to about 20 carbon atoms in such relative proportions that the atom ratio of metal-to-halogen is about 50:1 to 1:12. The halogen scavenger compounds can be halohydrocarbons both aliphatic and aromatic in nature or a combination of the two with halogens being attached to carbons either in the aliphatic or the aromatic portions of the molecule. The scavenger compounds may also be carbon, hydrogen, and oxygen-containing compounds, such as haloalkyl ethers, halohydrins, haloesters, halonitro compounds, and the like. Still other examples of scavengers that may be used in conjunction with the novel compounds of this invention either with or without hydrocarbolead compounds are illustrated in U.S. Patents 2,398,281 and 2,479,900-903, and the like. Mixtures of different scavengers may also be used. These fluids can contain other components as stated hereinabove. In like manner, fluids are prepared containing from 0.01 to 1.5 theories of phosphorus in the form of phosphorus compounds. To make up the finished fuels, the concentrated fluids are added to the hydrocarbon fuel in the desired amounts and the homogeneous fuel obtained by mixing, agitation, etc.

The ratio of the weight of metal in the form of a compound of this invention to lead in fluids and fuels containing the two components can vary from about 1:880 to about 50:1. When no lead is present, the latter figure becomes 1:0. A preferred range of ratios, however, when both the compounds of this invention and hydrocarbolead compounds are employed, is from about 1:63 to about 30:1.

10 The following examples are illustrative of fuels and fluids containing the coordination compounds described herein above.

Example I

To 1000 gallons of a commercial fuel having an initial boiling point of 90° F. and a final boiling point of 406° F. is added 15 grams of chromium as cycloheptatriene chromium tricarbonyl and the mixture is subject to agitation until the additive is distributed evenly throughout the fuel in an amount equivalent to 0.015 gram of chromium per gallon of fuel.

Example II

To 1000 gallons of the commercial fuel utilized in Example I, is added 600 grams of chromium as cycloheptatriene chromium tricarbonyl and 40 grams of methylcycloheptatriene molybdenum benzene. The mixture is then subject to agitation until the additives are distributed evenly throughout the fuel in amounts equivalent to 0.6 gram of chromium per gallon of fuel and 0.04 gram of molybdenum respectively.

Example III

To 10 parts of lead in the form of tetraethyllead in an antiknock fluid containing 0.5 theory of bromine as ethylene dibromide and 1.0 theory of chlorine as ethylene dichloride wherein the theories of halogen are based on the amount of lead present, is added 0.1 part of molybdenum in the form of chlorocycloheptatriene molybdenum tricarbonyl.

40 This fluid is then added to a commercial fuel having an initial boiling point of 82° F. and a final boiling point of 430° F. in an amount so as to provide 10 grams of lead and 0.1 gram of molybdenum per gallon.

Example IV

45 Into a fuel containing 0.1 gram of lead per gallon as diphenyl diethyllead, 1 theory of bromine as ethylene dibromide, and 0.2 theory of phosphorus in the form of tricresyl phosphate is added cycloheptatriene tungsten tricarbonyl in an amount equivalent to 1 gram of tungsten per gallon.

Example V

50 Eight grams of chromium per gallon as 1-phenyl cycloheptatriene chromium tricarbonyl is added to a gasoline having an initial boiling point of 116° F. and a final boiling point of 385° F. and which contains 70.1 percent paraffins, 15.6 percent olefins, and 14.3 percent aromatics.

Example VI

55 To 1000 gallons of a commercial fuel having an initial boiling point of 88° F. and a final boiling point of 390° F. is added 10,000 grams of molybdenum as cycloheptatriene molybdenum tricarbonyl titanium and the mixture subjected to agitation until the additive is distributed evenly throughout the fuel in an amount equivalent to 10 grams of molybdenum per gallon of fuel.

60 Certain of the fuels containing the cycloheptatriene metal coordination compounds as additives contain mixtures of two or more of these coordination compounds 65 containing similar metals, however consisting of dissimilar compositions in that various coordination substituents are adfixed to these similar metals.

Example VII

75 To a gasoline having an initial boiling point of 86° F.

and a final boiling point of 419° F. is added 60 grams of chromium as cycloheptatrienyl cycloheptatriene chromium tricarbonyl and 3 grams of chromium as bis(cycloheptatriene) chromium and the mixture subjected to agitation until the additives are distributed evenly throughout the fuel in an amount equivalent to about 0.063 gram of chromium per gallon of fuel.

The following examples illustrate the preparation of fluids containing the coordination compound additives of this invention.

Example VIII

To 10 parts of ethylphenyl cycloheptatriene chromium tricarbonyl is added 5 parts of ethylene dichloride and the mixture agitated until a homogeneous fluid results.

Example IX

A fluid is prepared comprising bis(cyclohexyl-cycloheptatriene) tungsten and ethylene dibromide in which the tungsten to bromine ratio is 1:8.

Example X

A fluid containing 3,5-dimethylcycloheptatriene tungsten tricarbonyl, ethylene bromohydrin, and 2,3-dichloro-1,4-dimethyl benzene is prepared in such proportions that for every 75 atoms of tungsten there are 1 atom of bromine and 2 atoms of chlorine.

The above fluids are added to hydrocarbon fuels in amounts so as to provide fuels containing 0.015 gram, 0.03 gram, 6 grams and 10 grams of transition metal per gallon.

Example XI

To 13.2 parts of lead in the form of tetraethyllead in an antiknock fluid containing 0.5 theory of bromine as ethylene dibromide and 1 theory of chlorine as ethylene dichloride wherein the theories of halogen are based upon the amount of lead present is added 0.015 part of molybdenum in the form of cycloheptatriene molybdenum tricarbonyl.

The fluid is then added to a commercial hydrocarbon fuel having an initial boiling point of 96° F. and a final boiling point of 410° F. in an amount so as to provide 13.2 grams of lead and 0.015 gram of molybdenum per gallon.

Other fuels and fluids are prepared in the same manner as illustrated herein above which contain other deposit modifying agents, such as boric acid, borate esters, boronic esters, etc. Likewise, lubricating oils can be prepared containing from about 0.1 to about 5 weight percent transition metal in the form of the cyclic conjugated olefin coordination compounds described thereinbefore. These lubricating oils when used in reciprocating engines were found to have a beneficial effect on engine cleanliness and in the reduction of combustion chamber deposits. In particular those embodiments of the additives of this invention wherein a metal such as molybdenum is associated with sulfur impart improved antiwear characteristics to the lubricant base stock.

The fuels to which the additive compositions of this invention are added may have a wide variation of compositions. These fuels generally are petroleum hydrocarbons and are usually blends of two or more components. These fuels can contain all types of hydrocarbons including paraffins, both straight and branched chain; olefins; cycloaliphatics, containing paraffin or olefin side chains; and aromatics containing aliphatic side chains. The fuel type depends on the base stock from which it is obtained and on the method of refining. For example, it can be a straight run or processed hydrocarbon including thermally cracked catalytically cracked reformed fractions, etc. When used for spark fired engines the boiling range of the components of gasoline can vary from 0 to about 430° F. Although the boiling range of the fuel blend is often found to be between an initial boiling point of from 80° F. to 100° F. and a final boiling point of

about 430° F. The above being true for ordinary gasoline the boiling range is a little more restricted in the case of aviation gasoline. Specifications for the latter often call for a boiling range of from about 82° F. to 338° F. with certain fractions of the fuel boiling away at particular intermediate temperatures.

To illustrate the antiknock effect of the cycloheptatriene metal additives of this invention tests are conducted by the Research Method of determining octane number. The Research Method of determining the octane number of the fuel is generally accepted as a method of tests which gives a good indication of fuel behavior in full scale automotive engines under normal driving conditions and the method most used by commercial installations in determining the value of a gasoline or additive. The Research Method of testing antiknocks is conducted in a single cylinder engine especially designed for this purpose and referred to as the CFR engine. This engine has a variable compression ratio and during the test the temperature of the jacket water is maintained at 212° F. and the inlet air temperature is controlled at 125° F. The engine is operated at a speed of 600 r.p.m. with a spark advance of 13° before top dead center. The test method employed is more fully described in the test procedure D-908-55 contained in the 1956 edition of "ASTM Manual of Engine Test Methods for Rating Fuels." The tests are conducted in a commercial fuel having an initial boiling point of 85° C. and a final boiling point of 420° C. Significant octane increase results are obtained when the Group VIB transition metals as the compounds described in this invention are employed in varying amounts to a multitude of diverse fuels as taught hereinbefore.

Another advantage which certain additives of this invention possess is their ability, when properly employed, to reduce the wear ordinarily encountered in engines. The amount of wear can be determined by the rate of loss of weight by the upper piston ring according to the method disclosed in U.S. Patent 2,315,845. The method of this patent involves determining wear by incorporating a radioactive substance in the surface of the piston ring normally subjected to abrasive wear, then abrading the surface in the presence of the lubricating oil which is capable of receiving abraded particles, and then determining the radioactivity of the lubricating oil. Thus, the wear is determined after operation of the engine containing the radioactive piston rings. It is found that when certain compositions of this invention are employed, considerably less wear is evidenced than in the absence of these compounds.

Examples of the hydrocarbon lubricating compositions of this invention include the following.

Example XII

To 10,000 parts of a petroleum hydrocarbon lubricating oil having an API gravity at 60° F. of 30.3, a viscosity at 100° F. of 178.8 SUS, a viscosity index of 154.2 and a pour point of -30, is sufficient 3-ethylcycloheptatriene molybdenum tricarbonyl to give a composition containing 5 percent molybdenum.

Example XIII

To a petroleum hydrocarbon oil having a viscosity at 60° F. of 30.5° API, a viscosity at 100° F. of 373.8 SUS, a viscosity index of 107.4, is added sufficient 1-phenylcycloheptatriene chromium tricarbonyl to give a composition containing 0.1 percent chromium.

Example XIV

To a quantity of an oil having a viscosity of 169.0 SUS at 100° F. and a gravity of 31.1° API at 60° F., is added sufficient cycloheptatriene tungsten tricarbonyl to give a composition containing 4 percent tungsten.

In the compositions of this invention effective use can be made of other additives which are known to the art, such as inhibitors, detergent-dispersants, pour point de-

pressants, viscosity index improvers, anti-foam agents, rust inhibitors, oiliness or film strength agents, dyes, and the like. Of the inhibitors which can be effectively used in combination with the compounds of this invention are sulfurized sperm oil, sulfurized terpenes, sulfurized paraffin wax olefins, aromatic sulfides, alkyl phenol sulfides, lecithin, neutralized dithiophosphates, phosphorus pentasulfideterpene reaction products, diphenylamine, phenyl-naphthyl amine, B-naphthol, pyrogallol, and the like. Typical of the detergent additives that can be used in the lubricant compositions of this invention are metallic soaps of high molecular weight acids, such as aluminum naphthenates, calcium phenyl stearates, calcium alkyl salicylates, alkaline earth metal petroleum sulfonates, alkaline earth metal alkyl phenol sulfides (barium amyl phenol sulfide, calcium octyl phenol disulfide, etc.), metal salts of wax-substituted phenol derivatives, and the like. Of the viscosity index improvers and pour point depressants, effective use can be made of polymers of the esters of methacrylic acids and higher fatty alcohols and the corresponding polymers of esters of acrylic acid and higher fatty alcohols. These and other additives which can be employed in the lubricant compositions of this invention will now be well known to those skilled in the art.

A procedure which can be employed in preparing the compounds of this invention involves the reaction between a compound of the type MX₂ wherein M is a transition metal as defined hereinabove and X and Y are electron donors such as those defined hereinabove which can be the same or different, with a cycloheptatriene compound.

The wide variation of pressures and temperatures can be employed in the above process dependent upon the reagent used and the reaction product desired. For example, temperatures of the range of 100° C. can be employed in the preparation of cycloheptatriene chromium tricarbonyl. In general, however, the aforementioned process employs temperatures ranging between about 50 to 500° C. Generally pressures ranging from atmospheric to 10,000 p.s.i. can be employed, however, in most instances, the pressure reaction vessel is employed and autogenous pressure utilized. Solvents generally are not employed in this process, however, are in some instances desirable to insure reaction control and the like.

In the working examples which appear hereinafter, all parts and percentages are by weight unless otherwise specified.

Example XV

Into a pressure vessel is introduced 264 parts of molybdenum hexacarbonyl and 92 parts cycloheptatriene. The

system is closed and heated under autogenous pressure. Following cooling of the autoclave the CO pressure is bled off to atmospheric pressure and thereafter the product cycloheptatriene molybdenum tricarbonyl is removed.

5 The crude cycloheptatriene molybdenum tricarbonyl may be further purified by sublimation onto a cold finger.

Example XVI

In a Vycor flask equipped with a stirrer and dropping funnel 92 parts of cycloheptatriene is added dropwise to a solution of 264 parts of molybdenum hexacarbonyl in 10 parts of toluene as a solvent. With stirring the flask is irradiated by means of ultraviolet or infrared light thereby causing carbon monoxide to be expelled from the reaction mixture. When the reaction ceases the toluene is boiled off under reduced pressure leaving the product cycloheptatriene molybdenum tricarbonyl, boiling as residue.

Example XVII

20 The process of Example XV is repeated using 1000 parts of toluene as a solvent.

Example XVIII

25 Following the procedure of Example XVI with the exception that 352 parts of tungsten hexacarbonyl is employed in place of 264 parts of molybdenum hexacarbonyl, 1000 parts of dioxane is utilized as a solvent, and a temperature of 100° C. is maintained on the system during the course of reaction thereby the desired product cycloheptatriene tungsten tricarbonyl is produced.

We claim:

1. A composition consisting essentially of a liquid hydrocarbon selected from the class consisting of hydrocarbon fuels and hydrocarbon lubricants containing from about 0.015 to 10 grams of a Group VIB transition metal per gallon as a compound having the formula AM(CO)₃ wherein M is an atom of a Group VIB metal and A is a cycloheptatriene molecule coordinated to said metal atom.
2. The composition of claim 1 where the additive is cycloheptatriene molybdenum tricarbonyl.
3. The composition of claim 1 where the additive is cycloheptatriene chromium tricarbonyl.
